Primary Examiner — Elizabeth J Oswecki(74) *Attorney, Agent, or Firm* — Notaro, Michalos & Zaccaria P.C.(57) **CLAIM**

The ornamental design for a device for an ATM card slot, as shown and described.

DESCRIPTION

FIG. 1 is a rear elevational view of a device for an ATM card slot showing my new design;

FIG. 2 is a top plan view thereof;

FIG. 3 is a front elevational view thereof;

FIG. 4 is a side elevational view thereof;

FIG. 5 is a front perspective view thereof;

FIG. 6 is a rear perspective view thereof; and,

FIG. 7 is an exploded rear perspective view thereof, the inner bracket removed for ease of illustration.

The parts shown in broken line form no part of the design.
